US00D942436S

(12) **United States Design Patent** (10) **Patent No.:** **US D942,436 S**
Lee (45) **Date of Patent:** **** Feb. 1, 2022**

(54) **WIFI REPEATER**

(71) Applicant: **MAKE GREAT SALES LIMITED**,
 Wan Chai (HK)

(72) Inventor: **Kin Choi Lee**, Wan Chai (HK)

(73) Assignee: **Make Great Sales Limited**, Hong
 Kong (HK)

(**) Term: **15 Years**

(21) Appl. No.: **29/716,649**

(22) Filed: **Dec. 11, 2019**

(51) LOC (13) Cl. **14-03**
 (52) U.S. Cl.
 USPC **D14/240**; D14/358

(57) **CLAIM**

The ornamental design for a WiFi repeater, as shown and described.

DESCRIPTION

FIG. 1 is a top isometric view of a WiFi repeater, in accordance with my design;

FIG. 2 is an exploded top isometric view of a WiFi repeater of FIG. 1;

FIG. 3 is a bottom isometric view of the WiFi repeater of FIG. 1;

FIG. 4 is a right side view of the WiFi repeater of FIG. 1;

FIG. 5 is a left side view of the WiFi repeater of FIG. 1;

FIG. 6 is a front view of the WiFi repeater of FIG. 1;

FIG. 7 is a rear view of the WiFi repeater of FIG. 1;

FIG. 8 is a top view of the WiFi repeater of FIG. 1; and,

FIG. 9 is a bottom view of the WiFi repeater of FIG. 1.
